DESIGN FOR A DISPLAY BOX

Samuel H. Geffner, New York, N. Y.

Application January 21, 1943, Serial No. 109,319

Term of patent 7 years

To all whom it may concern:

Be it known that I, Samuel H. Geffner, a citizen of the United States of America, residing in New York city, county of New York, and State of New York, have invented a new, original, and ornamental Design for a Display Box, of which the following is a specification, reference being had to the accompanying drawing, forming part thereof.

Fig. 1 is a front perspective view of a display box showing my new design.

Fig. 2 is a perspective view of the display box illustrating the top portion in open position.

The rear view of the display box is conventional.

The characterizing features of my design for the display box shown reside in the centrally located rectangular opening at the upper edge of the front panel of the lid and the cut-out in the upper edge of the front panel of the bottom portion of the box, all as shown.

I claim:

The ornamental design for a display box, substantially as shown and described.

SAMUEL H. GEFFNER.
